UNITED STATES PATENT OFFICE.

WILLIAM CRAINE, OF BROOKFIELD, NEW YORK.

FIRE-ESCAPE.

935,142.

Specification of Letters Patent. Patented Sept. 28, 1909.

Application filed June 30, 1908. Serial No. 441,105.

To all whom it may concern:

Be it known that I, WILLIAM CRAINE, a citizen of the United States, residing at Brookfield, in the county of Madison and State of New York, have invented a new and useful Fire-Escape, of which the following is a specification.

This invention relates to fire escapes and has for its object to provide a strong, durable and thoroughly efficient device of this character especially designed for use on school houses, hospitals, asylums and other buildings and by means of which the occupants of the building may reach the ground in safety in case of fire.

A further object of the invention is to provide a fire escape including a plurality of spiral tubes extending from the ground to the different floors of the building and each provided with an entrance and exit, said tubes being inclosed in a casing or housing so as to prevent the flames from coming in contact therewith.

A further object is to provide improved means for bracing the spiral tubes, and means for closing the entrance and exit passages of said tubes.

A still further object of the invention is generally to improve this class of devices so as to increase their utility, durability and efficiency.

Further objects and advantages will appear in the following description, it being understood that various changes in form, proportions and minor details of construction may be resorted to within the scope of the appended claims.

In the accompanying drawings forming a part of this specification: Figure 1 is a side elevation partly in section of a fire escape constructed in accordance with my invention. Fig. 2 is a transverse sectional view of Fig. 1. Fig. 3 is a perspective view of the entrance end of one of the spiral tubes.

Similar numerals of reference indicate corresponding parts in all of the figures of the drawings.

The improved fire escape forming the subject matter of the present invention comprises a tower 5 formed of concrete or other suitable material and preferably extended the entire height of the building, indicated at 6, said tower being substantially cylindrical in shape, as shown, and provided with a top piece or cap 7 forming a closure for the upper end of said tower.

Disposed within the tower 5 is a longitudinal rod or standard 8 around which is disposed a plurality of spiral tubes 9, said tubes being of different lengths and arranged to open on the different floors of the building so as to permit the occupants of said building to reach the ground in safety in case of fire in any portion of the building.

The entrance 10 of each spiral tube is normally closed by a pair of swinging doors 11, which latter open inwardly and are normally held in open position by suitable springs 12.

The lower ends of the tubes 9 extend through suitable openings in the walls of the tower 5 and are provided with exits 13 normally closed by co-acting spring actuated doors 14 arranged to open outwardly so that a person sliding down any one of the tubes may pass through the adjacent exit 13.

Extending laterally from the central rod or standard 8 are a plurality of radiating arms 15 having their terminal portions embedded or otherwise anchored in the wall of the tower, as indicated at 16, and their intermediate portions curved to conform to and adapted to receive the adjacent tubes 9 thereby to reinforce and strengthen the latter and hold said tubes in assembled position.

Attention is here called to the fact that the pitch of the tubes gradually decreases from the upper ends thereof to the exits 13 so as to allow the gradual descent of a person and thus prevent injury.

It will also be noted that the tubes at the base of the tower are intertwined so as to produce a strong, rigid structure.

It will thus be seen that in case of fire on any particular floor of a building it is merely necessary for a person to press the doors 11 inwardly and enter the adjacent tube 9, the inclination of the tube permitting the person or persons to slide through said tube to the ground in safety.

While the fire escape is shown in position on the outside of a building it is obvious that the same may be positioned within the building and that as many spiral tubes may be employed as there are stories or floors to the building.

Having thus described the invention what is claimed is:

1. The combination with a building, of a tower, a plurality of contiguous and intertwined spiral tubes disposed within the tower, and extending respectively from the

several floors of the building to the ground, each tube being provided with an entrance and an exit.

2. The combination with a building, of a 5 tower, a longitudinally disposed rod arranged within the tower; a plurality of contiguous intertwined spiral tubes encircling the rod, and extending respectively from the several floors of the building to the ground, 10 each of said tubes being provided with an entrance and an exit, and braces radiating

from the rod, and having their outer ends anchored in the walls of the tower, and their intermediate portions bearing against the adjacent tubes.

In testimony that I claim the foregoing as my own, I have hereto affixed my signature in the presence of two witnesses.

WILLIAM CRAINE.
